T. MUNRO

COVER FOR VEHICLE SPRINGS AND RESILIENT ATTACHING MEANS THEREFOR

Original Filed Jan. 20, 1925

Fig. 1.

UNITED STATES PATENT OFFICE.

THOMAS MUNRO, OF PHILADELPHIA, PENNSYLVANIA, ASSIGNOR OF ONE-HALF TO
CHARLES F. O'MULLEN, OF PHILADELPHIA, PENNSYLVANIA.

COVER FOR VEHICLE SPRINGS AND RESILIENT ATTACHING MEANS THEREFOR.

Application filed January 20, 1925, Serial No. 3,549. Renewed September 20, 1927.

The object of this invention is to provide improvements in lubricating spring-covers, particularly adapted for use upon the leaf-springs of automobiles, to keep them constantly oiled and thereby prevent any tendency of the springs to rust or squeak, and the leaves of the springs to stick together and thereby retard relative movement between them and proportionately decrease 10 the resiliency of the spring as a unit.

Another object is to provide in such a device a relatively thick layer of felt or other fibrous material adapted to lie adjacent the top of the spring, said layer being split 15 throughout a portion of its longitudinal extent to form separable parallel sections, one section being provided with an aperture and containing a ring of cork or other suitable material that is relatively stiff to prevent 20 the collapse of said section, said ring also providing a lubricant reservoir from which oil can pass into the subjacent felt section.

A further object is to surround this porous structure with a cover of substantially non-porous material having an aperture through 25 which lubricant is injected into said reservoir, and expansible spring fastening means extending between the opposite edge portions of said cover to secure the latter about 30 the spring.

Still another object is to provide for this purpose a fastening means, comprising a pair of members the opposite ends of which are adapted to extend through eyelets in 35 the opposed edge portions of the cover, the central portions of said members paralleling each other and each member having its inner end looped to form an eyelet through which the other member slidably extends, and a 40 coiled spring surrounding the parallel portions of said members and compressible between their respective eyelets.

And a still further object is to provide in such a device a closure for the oil inlet 45 aperture, said closure being preferably made of flexible material, fastened at one end to the material of the spring cover proper, and at its other end detachably fastened to said cover material by any suitable means, as for instance a so-called glove fastener, or to provide a male closure adapted to fit into and engage the sides of the inlet aperture in a manner similar to a glove-fastener.

With these and other objects in view, the

present invention comprises additional novel 55 details of construction and operation hereinafter fully brought out in the following description, when read in conjunction with the accompanying drawings, in which Fig. 1 is a central longitudinal section taken 60 through a portion of a vehicle leaf-spring and a lubricating spring-cover of my improved type disposed thereon; Fig. 2 is a bottom plan view of the spring and cover attached thereto; Fig. 3 is an enlarged fragmentary sectional view taken through the oil inlet aperture and the closure therefor; and Fig. 4 is a vertical transverse section on the line 4—4 of Fig. 1.

Referring to the drawings, the leaves 1 70 of the vehicle spring are shown as of different lengths, as is usually the case, the spring gradually diminishing in thickness from its center toward its ends at which, as well as at its center, it is suitably connected 75 to adjacent parts of the chassis in the customary way. As seen clearly in Fig. 4, the cover is formed of a sheet of flexible material which is preferably impervious to both 80 water and oil, and comprises a central portion 3 and two lateral portions 4, the central portion being adapted to lie in spaced relation with the upper surface of the spring, while the lateral portion extend 85 downwardly upon the opposite sides of the spring and prevent dirt and dust from entering between the several spring-leaves. Each of the lateral portions 4 at its lower edge is turned inwardly and reversely to form a reinforced margin 5, and provided 90 at spaced intervals with eyelets 6 the eyelets in the respective margins 5 being disposed substantially opposite each other.

Secured in any suitable manner to the undersurface of the central portion 3 is a 95 relatively thick layer of felt 7, which adjacent to one end portion is split to form parallel separable layers 8 and 9. Referring to Fig. 3, it will be noted that a single aperture 10 is punched through the upper layer 8, so as to form a recess in which may be inserted an annular member 11, preferably of fibrous material, such as cork, and itself having a central aperture 12, and the cover portion 3 immediately above or in line with the aperture 12 is punched to provide an aperture 13, which is reinforced and protected by means of an eyelet 14.

In order to normally close the aligned openings 12 and 13, a tongue 15 of flexible material is secured at one end by a staple 16 or other means to the cover section 3 and 6 felt sections 8 and 9, the central portion of said tongue being provided with a felt disc 17 secured to the tongue by means of a staple 18, and maintained in normally uniform contact with the eyelet 14 by providing the 10 free end portion 19 of the tongue with one section 20 of a glove-fastener, the other section 21 of the fastener is secured to and through the cover portion 3.

The inner surfaces of the lateral portions 15 4 of the cover are lined with a layer 22 of felt or the like, and the lower edges of these lateral felt sections are secured in the marginal portions 5 of the cover, said marginal portions being stiffened by means of a longitudinally extending relatively stiff yet flexible rod 23.

For the purpose of securing the cover in operative position upon the spring a novel form of fastening means is provided. As 25 clearly shown in Figs. 2 and 4, said means comprise a pair of wires 24 and 25 disposed in parallel relation with their inner end portions overlapping each other, the extremities of the outer or free ends of the wires being 30 preferably turned over on themselves so as to provide a neat and smooth finish. The inner end of each wire is bent so as to form a loop or eye 27 surrounding and freely slideable upon the adjacent wire, the plane of 35 the loop being generally normal to the axis of the body of the wire, and a coil spring 28 is disposed between the loops and surrounding both wires in such manner that by pulling the free ends of the wires apart the 40 spring will be compressed between the loops, the length of the spring when fully expanded being preferably a little less than the width of the vehicle spring to which the cover is designed to be attached. While the spring 45 is of course formed of suitably tempered wire so as to provide for the requisite resiliency, the wires 24 and 25 are desirably formed of non-tempered or only slightly tempered material so that they may be 50 readily bent when attaching the cover to the vehicle spring in the manner now to be described:

In employing this improved fastening means for attaching a spring-cover to a vehicle spring, the cover is positioned over the spring as shown in Fig. 4, and the oppositely extending aligned end portions of the wires inserted through opposed pairs of the eyelets 6. The free ends 26 are then 60 pulled laterally outwardly in opposite directions until a considerable compression is placed upon the spring 28, after which that portion of the wires shown in dotted lines and extending beyond the lateral portions 4 65 of the cover are bent downwardly and in-

wardly as shown in Fig. 4. Thereafter, as the vehicle rises and falls with the irregularities of the road, and the several leaves of the spring are flexed into different positions, the cover is permitted to conform to 70 the varying shape of the spring, the pairs of wires of each fastening element sliding relatively to each other and the springs 28 always taking up any slack or looseness in the lateral parts of the cover, thus keeping the latter 75 snugly in position against the spring irrespective of its constantly changing contour as the car moves over the uneven surface of the road.

In the operation of this device, after the 80 cover has been attached to a spring as hereinbefore described, the glove-fastener 20-21 is separated and the tongue 15 raised so as to expose the aligned apertures 12 and 13. A relatively heavy lubricant is then injected 85 into the aperture 12, which forms a reservoir and from whence the lubricant seeps throughout the fibrous structure of the felt layers 8 and 9, and their united portions 7, 90 so as to saturate all parts thereof the longitudinal extent of said cover.

The lubricant having thus substantially saturated the felt upon the top of the spring, that is, beneath the central section 3, it then seeps into and downwardly through the lateral sections of felt 22, with the result that the laterally opposite portions of the openings between the spring leaves are bathed in oil, and in addition to preventing foreign matter from entering between said leaves, the oil or 100 other lubricant is thus always available to seep into the openings between said leaves by capillary attraction to keep the relatively moving surfaces of the leaves adequately lubricated, with the result that the vehicle 105 rides more easily than when the springs are dirty, and the springs attain a considerably longer life by reason of their being more yielding and conversely less rigid.

In conclusion, the rods 23, besides reinforcing the edge portions of the cover, serve to prevent the cover from creeping upon the vehicle spring, or buckling towards one end as they maintain the cover in its original extended shape at all times. In 110 fact, this predetermined shape and position of the cover is so maintained even as the vehicle rises and falls, and the leaves of the spring, sliding one upon another, increase or decrease the effective thickness of the spring 115 as a unit. In this action the sides of the cover slide vertically along the sides of the spring, but this is permitted, and they are always maintained in the same uniform contact with the vehicle spring by reason of the 120 fact that the springs 28 yield to permit a greater separation of the opposite edge portions of the cover, and conversely bring said edge portions toward each other as the depth 125 of the vehicle spring is lessened.

- It will further be observed that when required the spring cover may be very readily detached from the vehicle spring by bending the turned over ends 26 of the fastening elements outwardly and upwardly to a position substantially parallel with the overlapping parts of the wires so as to enable the said ends to be slipped out of the eyelets 6 to thereby free the fastening elements 5 from the cover. The latter may be then readily lifted off of the spring and as readily replaced thereon and again secured in position by the fastening elements in the manner already described, and as the wires 24 and 10 15 20 25 30 35 40 45 50 55 60 65 70 75 80 85 90 95 100 105 110 115 120 125 130
- 25 of the elements are preferably of such material that they can be readily bent back and forth a number of times without breaking, it is thus possible to utilize the same fastening means each time that the cover is moved and replaced or to substitute a new cover for the old one without the necessity of employing new fastening means.
- It will of course be understood that the use of the improved spring cover fastening means which I have herein disclosed and claimed is not confined to any particular form or type of cover and I therefore do not desire or intend to in any way limit the use thereof to the particular form and style of cover shown and described herein, and further, that minor changes and modifications may be made in the design, construction and arrangement of the said fastening means and also of the said cover to facilitate their employment on particular forms or styles of vehicle springs or for other purposes as may be desired, without departing from the spirit and scope of the invention as defined by the appended claims.
- Having thus described my invention, what I claim and desire to protect by Letters Patent of the United States is:—
1. A cover for springs, comprising a layer of thick fibrous material adapted to lie against the surface of a spring, said layer being split throughout a part of its length to form parallel sections, one section being provided with an aperture through which lubricant is injected into the body of said layer.
  2. A cover for springs, comprising a layer of felt, said layer being bifurcated to provide separable parallel sections, one section being provided with an aperture through which lubricant is injected into the body of the layer.
  3. A cover for springs, comprising a layer of felt split to provide parallel sections throughout a portion of its longitudinal extent, an aperture in one section through which lubricant may be injected into the body of the layer, and an annular member providing a reservoir and positioned within said aperture so as to prevent the collapse of the apertured section.
  4. A cover for springs, comprising a layer
- of felt split to provide separable sections throughout a portion of its longitudinal extent, an aperture in one section, an annular porous ring providing a lubricant reservoir and positioned within said aperture so as to prevent the collapse of the apertured section of said layer, a cover around said layer and having extensions laterally thereof, said extensions being adapted to encircle the sides of a spring, means extending between the opposite free edges of said extensions to removably secure said cover upon the springs, and an aperture in said cover whereby lubricant may be injected into said reservoir and into the body of the felt layer.
5. In a spring cover, the combination of a member adapted to surround a spring and having spaced pairs of eyelets in its opposed marginal edge portions, and means extending through opposed eyelets to removably secure the cover to the spring and to permit a yielding separation between said edge portions in conformity with the movements of the spring, said means comprising a pair of members each having a laterally extending eyelet through which the other member extends, and a coiled compression spring surrounding the overlapping portions of said members and compressed between their respective eyelets.
6. In combination with a spring cover adapted to surround a spring and presenting adjacent the bottom of the spring opposed edge portions having aligned eyelets, attaching means comprising a pair of members the opposite ends of which extend through said eyelets, the central portions of said members paralleling each other and each member having its inner end looped to form an eyelet through which the other member slidably extends, and a compression coil spring surrounding the parallel portions of said members and compressible between their respective eyelets.
7. In combination with a spring cover comprising a flexible member adapted to cover the upper and side surfaces of a vehicle spring, expansible means comprising relatively slidable parallel wires connecting the opposite edges of the cover beneath the spring and operative to permit the cover to conform to the movements of the spring when the spring leaves slide one upon another.
8. In combination with a spring cover comprising a flexible member adapted to surround the upper and side surfaces of a vehicle spring, means to stiffen and reinforce the longitudinal edges of the side portions of the cover, and expansible means connecting said reinforced edges beneath the spring and comprising relatively slidable wires and a coil spring disposed thereabout, said means being adapted to maintain the cover snugly against the vehicle spring ir-

respective of relative movement between the leaves of said spring.

9. Means for operatively securing the free edges of a spring cover together comprising
5 a pair of wires disposed in parallel relation and overlapping each other for a portion of their respective lengths, one end of each wire being bent around the adjacent wire to slidably engage the latter, and a coil spring
10 positioned about both wires between said bent over portions.

10. Means for operatively securing the free edges of a spring cover together so as to permit relative movement therebetween
15 under operative conditions, said means comprising a pair of wires disposed in parallel relation and overlapping each other for a portion of their respective lengths, the inner end of each wire being bent in a loop about
20 the other wire and adapted to slide thereon, and a coil spring surrounding the overlapping portions of both wires and compressi-

ble between said loops as the wires are pulled outwardly away from each other.

11. In combination with a spring cover 25 comprising a flexible member adapted to cover the upper and side surfaces of a vehicle spring, means for connecting the opposite edges of the cover and comprising a pair of relatively movable interconnected elements respectively engaging the side edges of the cover and extending beneath the spring.

12. In combination with a cover adapted to surround the upper and side surfaces of 35 a vehicle spring, means connecting the opposite edges of the cover and comprising a pair of relatively movable interconnected elements respectively engaging the side edges of the cover and extending transversely beneath the spring.

In testimony whereof I have affixed my signature.

THOMAS MUNRO
